HIGHWAY CROSSING SIGNAL SYSTEM

Arthur E. Reid, Gates, N. Y., assignor to General Railway Signal Company, Rochester, N. Y.

Application May 31, 1940, Serial No. 337,993

3 Claims. (Cl. 246—130)

This invention relates in general to highway crossing signal systems for intersections of highways with railways, and has more particular reference to means for affording protection in situations where sidings enter a main track adjacent a highway crossing.

In a system of the character referred to, in connection with a main track on which traffic moves both east and west, it is desirable to give warning to highway traffic so long as a train is approaching the highway, but to discontinue the warning when the train is receding from the highway. In the event that a train should enter the main track from a siding, at the time a receding train is still on the approach section to the highway, with the usual interlocked relays employed in this type of system, no warning would be given of the train entering from the siding.

With the above and other objects in view, it is proposed, in accordance with this invention, to provide means whereby proper protection is given to highway traffic at all dangerous times.

Further objects, purposes and characteristic features of the present invention will appear as the description progresses, reference being made to the accompanying drawing, showing solely in a diagrammatic manner, and merely for the purpose of illustration, one form of invention which the invention can assume. In the drawing:

The single figure of drawing is a wholly diagrammatic showing of one embodiment of the present invention.

Referring now to the drawing, there is here represented a stretch of single track, constituted by track rails 4 and 5, across which passes a highway H. The main track is divided into usual insulated track sections by insulating joints 6, whereby to form an east approach section 1, a west approach section 2, and a central, middle, or highway section 3.

Entering the main track is a siding constituted by track rails 7 and 8, and this siding enters the main track adjacent the highway and within the west approach section 2, and is controlled by a track switch TS.

The track switch TS is of the spring switch type, of any usual form, wherein the switch can be thrown to either its normal or its reverse position, by any desired means, although for the purpose of illustration an operating means in the form of a hand switch stand HSS has been shown. Connected in the throw rod connection 9 is a spring biasing means 10 which

is arranged to operate so as to press the switch either full normal or full reverse depending upon in which position it has been placed by the hand switch stand. Any usual damping or buffer means can be employed in connection with the spring means if desired. As a result, this spring switch is biased to its operating position and can be moved by a train trailing it to its other position.

10 For example, the switch is shown in its normal position, for main line traffic, but a train passing onto the main line from the siding can move the switch against its spring bias means to reverse position, whereby to move a contactor 11 connected with the switch points to close contacts 12 and 13, and these contacts are arranged to be closed when the switch is in full reverse position, and to remain so closed until the switch is within about one-half inch of its full normal position.

15 Each track section is supplied with a usual source of energy, such as a track battery TB, and a track relay TR, each identified with the section with which it is associated by an exponent corresponding to the section number. For example, track section 1 has track battery TB¹ and track relay TR¹.

20 Usual interlocked relays XR¹ and XR² are employed having the usual two separate windings and separate armatures, and with any usual interlocking means between the armatures such as 14 and 15. These interlocked relays function in the usual manner, whereby, upon deenergization of relay XR¹, for example its armature

25 drops, and makes up its back point, and moves the lock or hook member 14 counterclockwise so as to move into the path of movement of the hook 15 of relay XR². Upon the deenergization of XR² prior to the reenergization of XR¹, the armature of XR² drops, to move lock 15 clockwise until engaged by lock 14, as shown, and thus prevent the armature of relay XR² from

30 making up its back points. The subsequent reenergization of relay XR¹ causes the armature thereof to pick up, as shown, but the lock 14 is retained in its latching position, and hence, in order to allow relay XR² to make up its back points, it is first necessary to release the latch by energizing the winding of XR² and then deenergizing the same. The operation of the interlocked relays as described above is the operation which occurs as an east bound train passes along the main track. Of course, the reverse cycle of operation takes place upon a west bound train passing along the main track.

These relays **XR1** and **XR2** can be of the construction disclosed in the Field Patent 1,824,131, granted September 22, 1931.

For protection of highway traffic, signals **S1** and **S2** are provided at opposite sides of the highway **H** at the intersection, and these signals are of any usual type either steady or flashing, but are shown here simply as steady light signals for the purpose of illustration. They are controlled by the interlocked relays, whereby both signals are energized, so long as either of the interlocked relays is making up its back points.

Employed in the system for the purpose of warning of a move from the siding into the main track while a receding train is still occupying the siding approach section is a stick relay **SR** which has connected across its winding a rectifier **25** whereby to make it somewhat slow to release while having quick pick-up characteristics.

Having described the apparatus employed in the system, an understanding of the operation of the system will be best obtained by considering various train movements.

As shown in the drawing a train or car **16** is shown passing eastward and in the west approach section **2**, and the various parts of the system are shown in the positions and conditions they have assumed, due to this movement.

When train **16** entered approach section **1**, track relay **TR1** released to deenergize interlocked relay **XR1** and thereby energize the highway signals **S1** and **S2** through contact finger **26** and back point of relay **XR1**, and a remaining circuit obvious from the drawing. As the train entered highway section **3**, relay **TR3** released to maintain the signal energized until the rear end of the train had passed out of highway section **3** whereupon interlocked relay **XR1** picked up through a circuit including contact finger **17** and front point of relay **TR3**, and contact finger **18** and front point of relay **TR1**, whereby to deenergize the signals, as should be the case since the receding train does not endanger highway traffic.

It can be seen that interlocked relay **XR2**, having an energizing circuit including contact finger **19** and front point of relay **TR2**, and contact finger **17** and front point of relay **TR3**, was deenergized upon the train entering section **3** at which time relay **XR1** was deenergized. Hence, even though relay **XR1** subsequently became reenergized, the armature of relay **XR2** was latched up as shown in the drawing, and though it is deenergized, due to the presence of the train in section **2**, it cannot make up its back point, and hence cannot energize the highway signals.

Assume now that a train **20** on the siding enters the main track in section **2**, while train **16** still occupies section **2**, and hence still maintains relay **XR2** latched up. Unless means be provided for releasing this latch, the train entering from the siding can approach and pass over the highway without having given any warning to highway traffic.

As set forth above, after one of the interlocked relays is latched up, and the other relay has become reenergized, in order to release the latch it is merely necessary to momentarily energize the latched up relay, in the case in point, relay **XR2**, whereby to permit the latching means, as **14**, of the other interlocked relay, to swing in a clockwise direction and out of the way.

Upon train **20** passing onto the main track, the

spring switch is trialed and is moved over to its full reverse position, thereby closing track switch operated contact **12** to thus complete a circuit for energizing the interlocked relay **XR2**, which circuit includes contact finger **17** and front point of relay **TR3**, contact finger **19** and back point of relay **TR2**, switch operated contact **12** in its closed position, and contact finger **21** and back point of the stick relay **SR**.

Upon relay **XR2** picking up, it closes a circuit for picking up stick relay **SR** which pick-up circuit includes contact finger **17** and front point, contact finger **19** and back point, contact finger **22** and front point of relay **XR2**, and the winding of relay **SR**.

The picking up of relay **SR** opens the energizing circuit for relay **XR2** at contact **21** whereby relay **XR2** releases. The releasing of relay **XR2** breaks the pick-up circuit for relay **SR**, but this relay remains up through a stick circuit which includes contact finger **17** and front point, contact finger **19** and back point, and its own contact finger **23** and front point.

With the release of the latching and the deenergization of interlocked relay **XR2**, the signals at the highway crossing are energized through contact finger **24** and back point of relay **XR2**, whereby to give adequate warning to highway traffic of the approach of the train **20** which is entering the main track from the siding and approaching the highway.

It is obvious that an east bound train instead of proceeding as is train **16**, past the siding, might enter the siding, in which case the track switch **35** would be moved by hand to its reverse position to permit the train to enter the siding. Unless provision be made against it, this movement of the switch would cause a display of the highway warning signals, and thus warn of a danger **40** which would not exist because the train is receding from the highway and thus would cause unnecessary delay and confusion.

Assume now, with the system all restored to normal, and no trains present on the track, that **45** an east bound train passes over the highway and onto the siding. As the train passes through sections **1** and **3**, the warning signals are given as described above, until the rear end of the train passes out of section **3**, whereupon the signals become deenergized. It is also to be assumed that the track switch **TS** is thrown by hand to reverse position while the train is still occupying section **3**. Accordingly, a circuit is completed for **50** picking up stick relay **SR** which circuit includes contact finger **17** and back point of relay **TR3**, and the switch operated contact **13** in its closed position.

It should be noted that, with track relay **TR3** deenergized, the circuit for energizing the interlocked relay **XR2** to release its latching, is not completed by movement of the track switch since this circuit included a front point of relay **TR3**. Thus, the movement of the switch under the circumstances outlined cannot effect an unlocking of the interlocked relay **XR2**, and thus the highway warning signal cannot become energized so that an unnecessary warning and delay is not entailed.

Upon this siding train passing off of section **70** **3**, a stick circuit is completed for stick relay **SR** which includes contact finger **17** and front point of relay **TR3**, contact finger **19** and back point of relay **TR2**, and contact finger **23** and front point of the stick relay, whereby to maintain the stick relay in picked up position and prevent the

energization of interlocked relay **XR2** by maintaining the energizing circuit for it open at contact finger **21**, of the stick relay. Thus, the operation of the switch to permit the east bound train to enter the siding is prevented from causing an unlatching of the interlocked relay **XR2**, and a resulting unnecessary and confusing highway warning.

It is obvious that, should there be a siding entering the main track in approach section **1**, track switch operated contacts and a stick relay and associated circuits could be employed in connection with interlocked relay **XR1** to protect against unnecessary and undesired highway warning in connection with this siding in the same manner as described above.

The above rather detailed description of one form which this invention can assume, has been given solely by way of example, and is not intended in any manner whatsoever in a limiting sense. The present application contemplates covering all the various modifications and variations of structure and arrangement as may occur from time to time as desirable insofar as they are not specifically excluded from the scope of this application by the appended claims.

Having described my invention, I now claim:

1. In a signal system for highway-railway crossings, a highway crossing a stretch of main line track, a highway signal at the crossing, a passing siding, a track switch connecting the passing siding to the main line adjacent the highway, an approach track section at each side of the highway, a middle track section interconnecting the approach sections, the approach section at the siding side including the track switch, two interlocked relays, associated, respectively, with the two approach sections, circuit means for displaying the signal and effective when either relay makes up its back point, an energizing circuit for each relay closed only when its approach section and the middle section is unoccupied, the relays being so interlocked that if one be deenergized, while the other is in deenergized position, the armature of the one is latched up so as to prevent its making up its back point until after said other is reenergized and then said one is reenergized, a stick relay, a second energizing circuit for the interlocked relay associated with the passing siding approach section and including a back point of the stick relay, a contact closed upon positioning of the track switch away from its full normal position and a contact closed only if the passing siding approach section be occupied, and a pick-up circuit for the stick relay including a front point of said passing siding approach section interlocked relay, and the contact closed only if said passing siding approach section be occupied.

2. In a signal system for highway-railway crossings, a highway crossing a stretch of main line track, a highway signal at the crossing, a passing siding, a track switch connecting the passing siding to the main line track adjacent the highway, an approach track section at each side of the highway, the one at the siding side

including, at an intermediate point, the track switch, a middle section of track interconnecting the approach sections, two interlocked relays, associated, respectively, with the two approach sections, circuit means for displaying the signal and effective when either relay makes up its back point, an energizing circuit for each relay closed only when its approach section, and the middle section, is unoccupied, the relays being so interlocked that if one be deenergized, while the other is in deenergized position, the armature of the one is latched against making up its back point until after said other is reenergized and then said one is reenergized, a stick relay, a second energizing circuit for the interlocked relay associated with the passing siding approach section and including a back point of the stick relay, a contact closed upon positioning the track switch away from its full normal position, a contact closed only if the passing siding approach section be occupied and a contact closed only if the middle section be unoccupied, a pick-up circuit for the stick relay including a front point of said passing siding approach section interlocked relay, and the contact closed only if said passing siding approach section be occupied, and the contact closed only if the middle section be unoccupied, and a stick circuit for the stick relay including a contact finger and front point of the stick relay constituting a shunt across the front point of said passing siding approach section interlocked relay.

3. In a highway crossing signal system, in combination, a stretch of main track crossing a highway, a highway signal at the crossing, an approach section of track at each side of the highway and each terminating short of the highway, a common highway section of track including the highway and interconnecting the adjacent ends of the approach sections, a normally open signal energizing circuit for each direction of traffic, a control means for each energizing circuit and responsive to track occupancy to close its circuit and energize the signal so long as its approach section or the common highway section is occupied, a passing siding, a trailable spring track switch, operable to assume either normal or reverse positions and spring biased to its then operated position connecting the siding with an intermediate point of one of the approach sections, interlocking means between the two control means, and normally preventing the occupancy of the approach siding section, by a vehicle receding from the crossing after having occupied the highway section, from energizing the signal, additional circuit means effective, when closed and then opened, to make the interlocking means ineffective, means closing the additional circuit means when the track switch is trailed away from its full normal position and the siding approach section is occupied and the highway section is unoccupied and means reopening said additional circuit after said additional circuit has been closed.

ARTHUR E. REID.
